Primary Examiner — Calvin E Vansant

Assistant Examiner — Cheng Chen

(74) Attorney, Agent, or Firm — Genius Patent APC;
Bruce Angus Hare(57) **CLAIM**

The ornamental design for an injection manifold as shown and described.

DESCRIPTION

FIG. 1 illustrates a top, front, right side perspective view of an injection manifold showing the new design;

FIG. 2 illustrates a top, front, right side perspective view thereof as mounted to a support structure;

FIG. 3 illustrates top plan view thereof as mounted to a support structure;

FIG. 4 illustrates a top plan view thereof;

FIG. 5 illustrates a bottom plan view thereof;

FIG. 6 illustrates a front elevation view thereof;

FIG. 7 illustrates a rear elevation view thereof;

FIG. 8 illustrates a left-side elevation view thereof; and,

FIG. 9 illustrates a right-side elevation view thereof.

The portions of the support structure depicted in broken line forms no part of the claimed design.

1 Claim, 7 Drawing Sheets
